UNITED STATES PATENT OFFICE.

MICHAEL F. BROGAN, OF LAWRENCE, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

LAST-PULLING MACHINE.

1,383,284.

Specification of Letters Patent.

Patented July 5, 1921.

Application filed September 24, 1917. Serial No. 192,954.

To all whom it may concern:

Be it known that I, MICHAEL F. BROGAN, a citizen of the United States, residing at Lawrence, in the county of Essex and State 5 of Massachusetts, have invented certain Improvements in Last-Pulling Machines, of which the following description, in connection with the accompanying drawings, is a specification, like reference characters on 10 the drawings indicating like parts in the several figures.

This invention relates to machines for separating shoes and their lasts. The invention is herein shown as embodied in a machine of the general type described and illustrated in United States Letters Patent, No. 1,203,571, granted Nov. 7, 1916, upon the application of John M. Benjamin.

As previously constructed, last pulling machines of the described type have included a spring coöperating with the last pulling mechanism and arranged to be tensioned responsively to the resistance offered by the counter portion of the shoe to lengthwise 20 heelward thrust of the last during the early stages of relative vertical movement of the last heel and shoe counter to clear each other partially to relieve the lengthwise 25 heelward thrust of the last and subsequently 30 effective to impel the last lengthwise of the shoe when the bottom of the last heel clears the top of the shoe counter. This spring has been of sufficient power to impel the last rearwardly with sufficient force to overcome 35 the resistance offered by the back stay of a high shoe but with some shoes of light construction the strength of the spring has been such that during said early stage of last and shoe separation it failed to yield sufficiently 40 to relieve the lengthwise heelward pressure of the last against the end of the counter with the result that the back seams of shoes were occasionally broken out.

A feature of the present invention consists in the combination with shoe and last separating mechanism organized for relative movement of shoe holding and last holding means to effect relative separating movement of the last and shoe, including relative 45 lengthwise movement of the last and shoe, effective to cause relative lengthwise thrust of a last heel and shoe counter during the 50 early stage of separation, of auxiliary means

coöperating with the shoe and last separating mechanism and effective to reduce said 55 relative lengthwise thrust of the last and shoe and subsequently effective to increase lengthwise relative thrust to relieve strain upon the forepart of the shoe upper. This augmented lengthwise thrust may be, and 60 preferably is, utilized to relieve the strain on the throat of the vamp at the point in the last pulling operation when the greatest strain would otherwise be placed upon it by the last, and is effective subsequently to accelerate the movement of the last lengthwise 65 rearwardly as soon as the last heel clears the shoe counter. The reduction of said lengthwise thrust during the initial portion of the last pulling operation enables the last heel 70 to be started without imposing too much lengthwise thrust against the counter portion of the shoe so that the last heel can begin to move downwardly out of the shoe along the line defined by the inside contour 75 of the shoe end, without injuriously straining the back seam.

In the use of machines of this type, it has also been found that in pulling the lasts from tightly lasted shoes having thin upper stock, the pull of the last heel will, in some cases, pull the counter portion of the shoe slightly relatively to the grippers between which it is clamped with yielding pressure, causing the counter grippers to 80 form slight wrinkles in the thin upper stock 85 adjacent to the rand crease.

My present invention provides, among other features, means arranged to grip the shoe heel unyieldingly to oppose relative 90 lengthwise and vertical movement of the shoe. The positive stop formed by the heel gripping means will, obviously, prevent wrinkle-forming movement of the shoe relatively to its counter grippers. The heel gripping means, in the specific embodiment 95 selected for illustration, is additionally novel and advantageous, for example, in that it provides a unitary structure comprising rigidly connected heel gripping means to engage opposite sides of a shoe-heel and a heel height gage; and also adjustment means by which the position of the grippers and gage may be varied for different styles of 100 shoes and heels. The gage and grippers are 105 arranged in determinate relation and have

the function, also, of shoe positioning means since they determine the vertical and longitudinal position of the heel end of the shoe.

5 While machines of the described type as previously constructed have been very successful in factory use, it has been found that the clamping pressure of the counter grippers against the shoe subsequently to 10 the withdrawal of the heel end of the last has, in a few cases, been sufficient to bend in and crush the counter. In order that the machine may be better adapted for all classes of work, this clamping pressure 15 should be susceptible of determinate variation to suit the requirements of different classes of shoes.

A further feature of the invention consists in means for determinately varying the 20 extent of shoe gripping movement which may be imparted to opposed members relatively movable to grip a shoe. This is effected through manually controlled means arranged positively to limit the extent of 25 clamping movement of a common actuator for said opposed members. In the illustrated and preferred embodiment of this 30 feature of the invention, the adjustment means has a relatively wide range, and since 35 the movement-limiting stop constituting said means has threaded adjustment, it will be evident that the shoe clamping movement of said actuator may be minutely varied. Additionally, this adjustment means is arranged 40 and positioned to be readily accessible to the operator and is quickly and easily manipulated.

In the use of machines of the illustrated 45 type as previously constructed, it has been found also that there are exceptional cases where the last sticks—as when tacks driven through the insole into the last have not been removed or when the shoe is of very abnormal shape—so that there is danger of 50 “breaking out” the shoe if the separation of the last and shoe by the machine is completed or persisted in. Damage to such shoes can only be prevented by releasing the shoe from its holding means as soon as it 55 becomes apparent to the operator that the last being pulled is sticking.

A further feature of the invention consists in a novel construction and arrangement for permitting the shoe and last manually to be withdrawn from said gripping 60 means by the operator during the period of separation of the last and shoe. By using only counter grippers and heel grippers, such as previously described and by adjusting the clamping pressure of the counter grippers approximately by the minimum pressure required to hold the class of shoes 65 being operated upon, it is possible for the operator quickly to pull the shoe downwardly and forwardly out of the grippers

as soon as it becomes evident that the last is sticking. The shoe thus treated may have its last subsequently removed without serious damage to the shoe by gradually easing the last out of the shoe by hand, an operation 70 which will not impose such heavy strain on the shoe upper as to cause it to be “broken out.”

As an additional feature of the invention, I have provided novel mechanism operative 75 prior to the relative last and shoe separating movement to pull lengthwise rearwardly the back stay portion of the top of a shoe to afford clearance for the last heel so as to insure clearance between the back stay and 80 the metal plate on the bottom of the last heel which is sometimes inaccurately positioned and projects slightly beyond the heel end. This mechanism, in the illustrative embodiment, is arranged to effect this operation automatically and in timed relation 85 to the shoe and last separation. Preferably, and as illustrated, it is effected coincidently with the clamping of the shoe and prior to and independently of the last and shoe separating movement.

The invention includes, as a further feature, grippers mounted to engage opposite sides of the shoe, which are constructed and arranged for adjustment to present their 90 opposed gripping faces in determinate angular relation converging rearwardly of the shoe. In the illustrated embodiment means are provided for adjusting said grippers to vary their angle of convergence to suit the 100 requirements of different types of shoes. The grippers are also mounted for yielding movement transversely of the shoe and are arranged yieldingly to engage the opposite sides of the shoe counter to clamp the shoe 105 between them. The provision for yielding movement enables one adjustment of the counter grippers to accommodate a relatively wide range of shoes of a given style, and the adjustment means provided are of such character that the angle of convergence may be 110 quickly and easily changed by the operator.

The described and other features and advantages of the invention will be more fully understood from the following description, 115 in connection with accompanying drawings which show an illustrative embodiment of the invention and will then be particularly pointed out in the claims.

Figure 1 of the drawings is a side elevation of a machine of the described type embodying the features of the present invention, part of the frame being broken away to disclose interior mechanism;

Fig. 2 is a fragmentary perspective view 120 of the last holding, shoe gripping and upper pulling mechanisms;

Fig. 3 is a top plan view of the counter grippers; and

Fig. 4 is a fragmentary side elevation 130

showing the heel grippers and upper pulling device in coöperative relation to a shoe.

For convenience, the illustrative machine, except as to the novel features of the present invention, corresponds substantially to the machine described and illustrated in the Benjamin patent previously referred to, and corresponding parts are identified by similar reference characters. For the purposes of the present specification, a description in detail of the construction and operation of illustrated mechanism corresponding to that of the Benjamin patent is unnecessary since reference may be had to the description of the correspondingly numbered parts in said patent.

Briefly, the illustrated machine comprises a heavy upright column 2 designed to stand on a floor or other support and having bearings 20 for a power shaft 4 driven through a clutch member 8 when engaged with a continuously rotating pulley 6 loose on said shaft. The clutch is thrown in by depressing a treadle 22 which through associated parts 25 causes a connected cam shaft to be turned through a half revolution (representing one cycle of the machine) and automatically stops the shaft at the end of said half revolution. The cycle of operations is repeated by again depressing treadle 22.

Rotation of shaft 4, through certain worm gearing 40, 42, turns the cam 36 on cam shaft 38 through a half revolution. Rotation of the cam 36 through this half revolution first acts to clamp a positioned shoe between certain shoe gripping means, and then is effective to pull the last from the gripped shoe by certain mechanism operatively connected with means to engage the last in the gripped shoe.

The shoe gripping means are supported in a head on the top of the machine column, this head comprising a base 71 suitably bolted to the top of the column and having outwardly diverging arms 73 terminating in opposed bearings 77. The base plate 71 is provided with a housing 711 in which is guided for movement toward and from the front of the machine a plunger 72 having its forward end rigidly connected with a gripper operating cross bar 74 and normally pulled rearwardly in a direction to hold the grippers in retracted position by means of coiled springs 70. The rear end of the plunger 72 terminates adjacent to the upper end of a bell crank lever 68 journaled in the column at 66 and having a roll at its lower end engaging a peripheral cam face on the cam 36 (Fig. 1). This peripheral cam face is figured to lift the lower end of the bell crank and to cause the upper end of the bell crank to engage the plunger 72 and move the cross bar 74 forwardly to close the grippers upon the shoe upon the initial turning movement of the cam 36. Thereafter, the cam is opera-

tive to maintain the grippers closed upon the shoe until just before the completion of the cycle, when the grippers are released.

The means for gripping the shoe, according to the present invention, comprises opposed members relatively movable to grip the counter portion of the shoe, and means to engage the heel of the shoe in a manner unyieldingly to oppose relative lengthwise and downward movement of the shoe. In the illustrative machine, links 80 (Fig. 3) attached to the opposite ends of the cross bar 74, are connected to bell cranks 82 pivoted at 84 in recesses in the arms 73 and having their forward ends pivotally connected to the inner ends of rods 86. The outer ends of these rods are threaded into studs swiveled in ears laterally offset from tubular carriers 56 sliding in the bearings 77. Stems extend lengthwise through the carriers 56 and bearings 77 and are provided with abutment washers between which and the inner ends of tension adjusting sleeves 93 threaded into the outer ends of the carriers, coiled springs 59 are interposed. These stems project inwardly from the inner ends of the bearings 77 and carry opposed counter gripping members of novel construction.

Each gripping member includes a base 87 rigidly secured to the inner end of one of said stems and having a curved seat to receive the correspondingly curved base of a holder 89 within which is seated a pad of resilient gripping material, such as rubber. The inner faces of these pads are arranged to engage opposite sides of the counter portion of a shoe positioned between them and may or may not be concaved both vertically and longitudinally. Preferably, and as shown in Fig. 2, their gripping faces extend in a straight line longitudinally of the shoe. The holders 89 and their gripping pads are arranged for adjustment to present rearwardly converging gripping faces between which the counter portion of the shoe is inserted. The angles of convergence of these gripping members may be varied by adjusting the holders 89 upon the curved seats of the bases 87, this adjustment means, in fact, permitting adjustment of the grippers independently and from a parallel relation to any desired angular relation. For this purpose the holders are provided with clamping bolts 91 extending outwardly through slots in their bases 87 and arranged independently to vary the angle of convergence of their gripping members.

This arrangement of the gripping members enables them to have a yielding wedging engagement with the counter portions of shoes when they are inserted between them, the springs 59 and the convergence of the gripping faces permitting one adjustment of the gripping members to accommodate a relatively wide range in sizes of shoe 130

counters. The tension of the springs 59 may be adjusted, when desired, by the threaded sleeves 93 through which the outer ends of the stems freely slide.

5 As previously stated, it is desirable, in order to avoid crushing in the counter after the heel of the last has been pulled from within the counter portion of the shoe determinately to control and limit the clamp- 10 ing movement of opposed gripping members which are relatively movable to grip the counter portion of the shoe between them. This is true as to all gripping members of this character and is particularly 15 advantageous in the use of counter grippers of the described construction, since slight relative movement of the opposed gripping members is sufficient firmly to clamp the shoe. Accordingly, I have provided a stop 20 member, illustrated herein as a threaded sleeve 95 at the front of the frame screwing into an enlargement of the bore through which the gripper actuating plunger 72 is guided. This sleeve is provided with an 25 enlarged head located in the rear of the cross bar 74 which forms a common actuator for the opposed gripping members. The head of this sleeve acts as a stop to limit the extent to which the cross bar 74 30 may be pulled rearwardly by the springs 70, and to limit the extent to which the cross bar 74 and the connected gripping members may be moved by determinately varying the position of the end of the plunger 72 relatively to the upper end of the cam actuated 35 bell crank lever 68. This adjusting member, it will be noted, is positioned and arranged for quick adjustment by the operator and because of its threaded engagement with the 40 frame, is susceptible of relatively minute variations in adjustment.

Coöperating with the counter gripping members are certain heel gripping means of novel construction, arranged unyieldingly 45 to hold the shoe against movement during the pulling of the last. A bracket 133 is adjustably secured to the plate 71 at the front of the machine and extends upwardly forming a vertical bearing 135, and thence 50 extends outwardly over the position occupied by the heel of a shoe engaged between the counter grippers. From its forward end rearwardly this extension is slotted to receive the upper end of a threaded 55 stem 137. The lower end of this stem is flattened and embraced between bifurcations 139 upstanding from a heel engaging member which is of integral construction and is rigidly secured to the lower end of the stem 60 by suitable fastening means. This member is formed to provide a horizontally extending portion 141 arranged to engage over the top lift of a shoe heel and forming a heel height gage, and with a rearwardly offset 65 depending portion terminating at its lower end in outwardly diverging arms 143 providing a substantially V-shaped gripping member. These arms are adapted to have wedging engagement with opposite sides of a shoe heel unyieldingly to oppose lengthwise rearward and downward movement of a shoe gripped thereby. The heel height gage member 141 is in determinate relation to these gripping arms and in combination these parts act as positioning means for the 70 shoe, since they determine the position of the heel end of the shoe. The threaded stem carrying this heel gripping member is provided with suitable clamping nuts and is adjustable vertically for different 75 heights of heels and lengthwise of the bracket for different sizes of shoes and styles of heels. Preferably, to prevent injury to the upper materials of the shoe and to prevent marring of the finish of the shoe, 80 the heel height gage and the side gripping arms are covered with leather or other suitable material.

The last within the shoe which is positioned between the counter gripping means 85 with its heel engaged and located by the heel gripping and positioning means previously described, is carried by a heel pin 142 upstanding from a carrier 144 which, in machines of the described type, is arranged 90 to be swung upwardly by the operator to position the shoe for coöperation with the heel gripping and counter gripping means, and is operated through the cam 36, subsequently 95 to shoe gripping movement of the counter 100 grippers, to pull the last from the gripped shoe. The inner end of the carrier arm 144 is pivoted to the upper arm 146 of a bell crank lever which is pivoted to the upper end of a plunger 150 positioned rearwardly 105 of the heel end of a gripped shoe. The lower end of the plunger is attached to the front end of a link 166 arranged to be swung downwardly through a thrust bar 172 operated from the cam wheel 36, as described 110 in the Benjamin patent referred to, the position of the plunger rearwardly of the heel end of the shoe and the connections to carrier arm 144 causing the heel end of the last to exert lengthwise thrust against the shoe 115 counter as the plunger and last are moved downwardly. A rod 154 is pivoted at its upper end to the forward end of the arm 152 of the bell crank lever and has its lower end extending through a bore in a bracket 155 120 extending from and carried by the plunger 150. The rod 154 has sleeved upon it two coiled spring sections of unequal length and strength. The upper and longer spring section 157 is sleeved on the rod 154 between 125 the bell crank lever arm 152 and the upper and closed end of a cupped sleeve 156. The lower, shorter and weaker spring section 158 is sleeved on the rod between the bracket 155 and the sleeve 156, and extends within the 130

cupped portion of the sleeve. In the normal position of the parts the lower edge of the cupped sleeve is spaced from the bracket, so that upon downward movement of the 5 plunger 150, the resistance offered by the heel end of the shoe to the lengthwise thrust of the last will react against arm 146 of the bell crank lever and will swing downwardly the arm 152 against the tension of the weaker 10 spring 158 which permits a quick reduction of the lengthwise thrust of the last heel against the shoe counter during the initial stage of separation and until the lower edge of the cupped sleeve 156 engages the bracket; 15 thereafter during further downward movement of the plunger 150, continued resistance by the end of the shoe to lengthwise thrust of the last heel will continue to react against arm 152 and will compress the 20 stronger spring section 157 between the bell crank and the upper end of the cupped sleeve until the last heel clears the shoe counter, this spring offering relatively greater resistance and serving, when compressed, to 25 augment the lengthwise thrust of the last heel, thereby relieving the strain against the forepart of the upper and subsequently after the last heel clears the shoe counter, serving to accelerate the lengthwise movement of the last.

As previously stated, I have provided means for pulling lengthwise rearwardly the back stay portion of the top of a shoe, conveniently illustrated as a high shoe, to afford 35 clearance between the extremity of the heel of the last and the inside of the shoe top during relative separating movement of the shoe and last. The embodiment of this means selected for illustration comprises a 40 support 145 having an upstanding stem 147 detachably and adjustably supported in the vertical bearing 135 of bracket 133. The lower end of this support is bifurcated to form laterally spaced ears between which 45 is pivotally mounted the upper end of a cylindrical horn holder 149 having an upstanding finger extension 151 positioned forwardly of the gripper-operating cross bar 74. The alined front edge of the cross bar 50 is preferably rounded for sliding contact with said finger, as best seen in Fig. 4.

The holder 149 is formed with a socket in which is seated a hollow plug 153 having a coiled spring seated therein with one end 55 abutting the closed upper end of the plug and the other end anchored to an abutment pin extending transversely through alined bores in the holder 149 and through radially alined elongated slots in the sides of 60 the plug 153. The lower end of the plug is notched to receive and hold the rear end 155 of a bowed, upwardly curving spring blade, the forward and upper portion of which is flared laterally and curved forming 65 a horn member 163. This member is ar-

ranged to engage the inside back stay portion of the top of the illustrated high shoe and is normally held in raised position by the coiled spring acting against the plug 153 but may be pulled momentarily downward by hand if necessary to position the horn so as to clear the top edge of the shoe which is being swung upwardly and backwardly by the operator into coöperative relation to the counter grippers. A coiled spring 159 connects the finger 151 to an arm 161 rigidly connected to and extending rearwardly from support 145, and serves to maintain the finger in engagement with the front edge of the cross bar 74 in all positions of the bar. 80

In the inoperative position of the machine with the cross bar 74 retracted by its springs 70 to engage the stop 95, the horn is swung upwardly and forwardly by spring 159 to a position to coöperate with the top of a high 85 shoe which is being positioned between the counter grippers. If necessary, the operator may pull the horn downwardly against the tension of the plug spring to afford clearance for the top edge of the shoe, the 90 subsequent release of the horn positioning the top edge of the shoe between the arms of the substantially U-shaped member formed by the spring horn blade and its holder. When the treadle is operated to start 95 the machine, the forward movement of cross bar 74 moves the counter grippers into clamping engagement with the shoe and coincidentally moves the finger 151 to swing the horn 163 lengthwise rearwardly of the shoe, 100 stretching the back stay portion of the top of the shoe lengthwise rearwardly to provide clearance between the extremity of the last heel and this portion of the shoe top when the last is subsequently pulled from 105 the shoe in the continued operation of the machine. The horn with its holder and support may be adjusted for use with either high or low shoes. As shown in Fig. 4, it is arranged for operation upon the top of a 110 high shoe but it will be evident that, by bodily adjustment upwardly, it may be positioned to coöperate with the counter portion of low shoes.

In operating upon a shoe and its last (it 115 being assumed that the counter grippers have been adjusted to the appropriate angle for the class of shoes to be operated upon and that the heel positioning means and stop 95 have been similarly adjusted), the workman 120 mounts the last on the last pin 142 and swings the carrier 144 upwardly to engage the heel of the shoe with the height gage 141 and side gripping arms 143, with the counter portion of the shoe positioned between the counter grippers. If a high shoe 125 is being operated upon the top is inserted in rear of the horn 163 as seen in Fig. 4. The machine is started when the shoe has been properly positioned, the counter grip 130

- pers and the horn being first operated, as previously described, to clamp the shoe and to stretch the back stay portion of the shoe top, and the plunger 150, bell crank lever 146 and carrier 144 are subsequently pulled downwardly in the continued operation of the machine, changing their relative positions and lines of pull in response to the resistance offered to separation by the shoe 146 and carrier 144 are subsequently pulled downwardly in the continued operation of the machine, changing their relative positions and lines of pull in response to the resistance offered to separation by the shoe 10 parts. When the bottom of the last heel clears the counter portion of the shoe, the spring 158 which has been compressed in pulling the last from the shoe, exerts additional lengthwise thrust against the last which is of substantial assistance in overcoming the resistance offered by the top of a high shoe and substantially increases the speed of separation. Since the lengthwise 15 rearward movement of the last under the influence of the compressed spring has a very substantial component of vertically downward movement, the horn will ordinarily be cleared by the diagonally downward and rearwardly moving last, or if it should be in the path of movement of the last, is swung rearwardly by contact with the last out of said path of movement against the tension of the coiled spring 159.
- 30 At the beginning of the pulling operation, if the last for any reason should stick, the operator, who should temporarily retain his hold on the handle of the last carrier, may quickly pull the carrier with the last and shoe forwardly away from the counter and heel grippers, turning the bell crank lever against the tension of springs 157—158. This is permissible because the forwardly diverging faces of the heel and counter grippers offer practically no resistance to this movement although opposing rearward and downward movement in the normal operation of the machine by reason of their wedging engagement with the shoe which is increased rather 35 than diminished by the lengthwise rearward thrust of the last against the shoe.
- Having thus described my invention, what I claim as new and desire to secure by Letters Patent of the United States is:—
- 50 1. A machine of the class described, having, in combination, a shoe holder, a last holder, mechanism for relatively moving said shoe holder and said last holder to effect relative movement of a last and its shoe, to separate said last and shoe, and auxiliary means coöperating with said mechanism effective to cause lengthwise relative thrust of the last heel and shoe counter and subsequently effective to augment said lengthwise relative thrust to relieve strain upon the forepart of the shoe upper.
2. A machine of the class described, having, in combination, a shoe holder, a last holder, mechanism for relatively moving said
- shoe holder and said last holder to effect relative movement of a last and its shoe, including relative lengthwise movement to separate said last and shoe, and auxiliary means coöperating with said mechanism effective to augment the lengthwise relative thrust of the last heel and shoe counter at a point in the last and shoe separating movement subsequent to the initiation of said movement and prior to the point when the bottom 75 of the last heel clears the top of the shoe counter.
3. A machine of the class described, having, in combination, a shoe holder, a last holder, mechanism for relatively moving said shoe holder and said last holder to effect relative movement of a last and its shoe, including relative lengthwise movement, to separate said last and shoe, and auxiliary means coöperating with said mechanism effective to cause lengthwise relative thrust of the last heel and shoe counter and subsequently effective to augment said lengthwise relative thrust to relieve strain upon the forepart of the shoe upper, said means being thereafter operative to accelerate the relative lengthwise movement of the shoe and last when the bottom of the last heel and the top of the shoe counter have cleared each other. 95
4. A machine of the class described, having, in combination, a shoe holder, a last holding spindle, mechanism for relatively moving said holder and said spindle to effect relative movement of a last and its shoe, to separate the shoe and last, and successively operative auxiliary means coöperating with said mechanism and effective, first, to cause relative lengthwise thrust of the last heel and shoe counter and then to augment said relative lengthwise thrust of the last heel and shoe counter prior to the point when the bottom of the last heel clears the shoe counter. 100
- 105 5. A machine of the class described, having, in combination, a shoe holder, a last holding spindle, mechanism for relatively moving said holder and said spindle to effect relative movement of a last and its shoe, including relative lengthwise movement, to separate the shoe and last, and successively operative auxiliary means coöperating with said mechanism and effective, first to cause relative lengthwise thrust of the last heel and shoe counter and then to augment said relative lengthwise thrust of the last heel and shoe counter prior to the point when the bottom of the last heel clears the shoe counter. 110
- 115 6. A machine of the class described, having, in combination, shoe gripping means, a last holder, mechanism for moving the

last holder relatively to the shoe gripping means to move the last from its shoe by movement of the last, and successively operative auxiliary means coöperating with 5 said mechanism and effective first to cause lengthwise thrust of the last heel against the shoe counter and then effective before the bottom of the last heel has cleared the top of the shoe counter to augment said lengthwise thrust of the last heel to relieve 10 strain against the forepart of the shoe upper.

7. A machine of the class described, having, in combination, a shoe holder, a last holding spindle, mechanism for relatively 15 moving said holder and said spindle to effect relative movement of a last and its shoe to separate the last and shoe, and differentially powered and successively operative auxiliary spring means coöperating with said 20 mechanism and effective, first to yield to cause lengthwise relative thrust of the last heel and shoe counter responsively to the resistance offered by the shoe counter to said thrust, and then to interpose increased 25 resistance effective to augment the lengthwise relative thrust to relieve strain against the forepart of the shoe upper.

8. A machine of the class described having, in combination, shoe holding means, last holding means, mechanism for moving the 30 last holding means to pull the last from the shoe in a generally diagonal direction having one component lengthwise heelward of the shoe, and a plurality of differentially-powered springs auxiliary to said mechanism and coöperating with the last holding means, including a relatively weak spring 35 arranged to yield responsively to the resistance offered by the shoe counter to lengthwise thrust of the last heel during the initial 40 stage of last pulling movement to cause lengthwise heelward thrust of the last heel against the shoe counter and a relatively strong spring subsequently operative to increase the lengthwise heelward thrust.

9. A machine of the class described having, in combination, a shoe holder, a last holding spindle, mechanism for relatively moving said holder and said spindle to effect 45 relative movement of a last and shoe, including relative lengthwise movement, to separate said last and shoe, and differentially powered spring means auxiliary to and co-operating with said mechanism including 50 one relatively weak spring means arranged to yield responsively to the resistance offered by the shoe counter to relative lengthwise thrust of the last heel and shoe counter during the initial stage of last and shoe 55 separation to cause lengthwise strain against the counter portion of the shoe, and a relatively stronger spring means subsequently effective to increase the lengthwise strain against the counter portion of the shoe and 60 to accelerate said relative lengthwise move- 65

ment after the bottom of the last heel and the top of the shoe counter clear each other.

10. A last pulling machine having, in combination, shoe holding means and last removing means comprising a plunger movable along a line substantially perpendicular to the plane of the shoe bottom and rearwardly of the shoe, a bell crank lever carried by said plunger, a forwardly extending last carrier pivoted to one end of said bell crank 70 lever, and two springs acting against the other end of said lever, one of said springs being weaker than the other and being arranged for compression by the bell crank lever prior to compression of the stronger 75 spring.

11. In a last pulling machine, a last holding spindle, a carrier for said spindle, a supporting member for said carrier pivoted for swinging movement, and two springs acting 80 against said member and yieldingly opposing swinging movement of said member in one direction, one of said springs being weaker than the other and being arranged for compression prior to compression of the 85 relatively stronger spring.

12. A last pulling machine having, in combination, shoe holding means, and last removing means comprising a plunger, a bell crank lever fulcrumed on the plunger, a last 90 carrier pivoted to one arm of the bell crank lever, a last holder on said carrier, a rod pivoted to the other arm of said bell crank lever and guided in a bracket carried by 95 said plunger, and two concentric, successively compressible spring sections mounted on said rod between said bell crank lever and said bracket.

13. A last pulling machine having, in combination, shoe holding means, and last removing means comprising a plunger, a bell crank lever fulcrumed on the plunger, a last carrier pivoted to one arm of the bell crank lever, a last holder on said carrier, a rod pivoted to the other arm of said bell crank lever 100 and guided in a bracket carried by said plunger, a cupped sleeve on said rod with its lower edge above the bracket, an elongated coiled spring on said rod between said sleeve and the bell crank lever, and a shorter and 105 weaker spring on said rod between said bracket and sleeve and extending within said sleeve.

14. In a machine for effecting the separation of a shoe and its last, last holding 110 means, shoe holding means and mechanism for relatively moving said holding means to separate said shoe and its last, said shoe holding means comprising rigid means arranged to grip opposite sides of the heel of 115 the shoe and unyieldingly to oppose lengthwise and vertical movement of the shoe relatively to said means.

15. A last pulling machine having, in combination with last holding means and shoe 120

- counter gripping means, means arranged to grip the heel of the shoe and unyieldingly to oppose lengthwise and vertical movement of the shoe relatively to said gripping means 5 and mechanism for effecting relative movement of the last holding means and the shoe gripping means to separate the shoe and its last.
16. In a machine of the class described 10 having, in combination, means to hold a last, means to engage and hold the counter portion of a shoe, means arranged to have wedging engagement with opposite sides of the heel of the shoe and constructed unyieldingly to oppose lengthwise and vertical movement of the shoe relatively to said wedging means, and mechanism for effecting relative movement between said last holding means and the shoe holding means 15 20 to effect separation of the shoe and its last.
17. In a machine for effecting the separation of a shoe and its last by relative movement of last holding means and shoe gripping means, means to engage opposite sides 25 of the counter portion of a shoe with yielding clamping pressure, in combination with means arranged to grip the heel and unyieldingly to oppose relative lengthwise and vertical movement of the shoe.
18. In a machine for pulling the last from a shoe while the shoe is gripped and held for the pulling of the last, last holding means movable to pull the last from a gripped shoe and mechanism for moving the 30 last holding means to pull the last, and shoe gripping means comprising means to engage opposite sides of the counter portion of a shoe with yielding clamping pressure and means rigidly to engage the heel unyieldingly to oppose relative lengthwise and vertical movement of the shoe.
19. In a machine for effecting the separation of a shoe and its last by relative movement of last holding means and shoe gripping means, means to engage opposite sides 45 of the counter portion of a shoe with yielding clamping pressure and means arranged for wedging engagement with opposite sides of the heel unyieldingly to oppose relative lengthwise and vertical movement of the shoe.
20. In a machine for effecting the separation of a shoe and its last by relative movement of last holding means and shoe gripping means, means to engage and hold the heel of the shoe against relative movement comprising rigidly connected members arranged for wedging engagement with opposite sides of the heel, and a gage member in 50 determinate relation thereto and arranged to engage the face of the top lift of the heel.
21. In a machine for effecting the separation of a shoe and its last by relative movement of last holding means and shoe gripping means, a unitary construction comprising 55
- ing a gage plate to rest over the top lift of the heel and rigidly connected gripping members to engage the opposite sides of the heel constructed unyieldingly to oppose relative lengthwise and vertical movement 70 of the shoe.
22. In a machine for effecting the separation of a shoe and its last by relative movement of last holding means and shoe gripping means comprising a rigidly supported V-shaped member arranged for wedging engagement with opposite sides of the heel of the shoe unyieldingly to oppose relative lengthwise and vertical movement of the shoe, and a rigidly connected heel height gage in determinate relation thereto arranged to engage the face of the top lift of the heel. 75
23. In a machine for effecting the separation of a shoe and its last by relative movement of last holding means and shoe gripping means, heel positioning and holding means comprising a rigid bifurcated member arranged to have wedging engagement 80 with opposite sides of the heel and an integrally connected heel height gage arranged to engage the face of the top lift of the heel. 85
24. In a machine for effecting the separation of a shoe and its last by relative movement of last holding means and shoe gripping means, opposed members relatively movable to grip a shoe, and means for determinately varying the amount of shoe gripping movement which may be imparted 90 to said members. 95
25. In a machine for effecting the separation of a shoe and its last by relative movement of last holding means and shoe gripping means, opposed members connected for 100 relative and simultaneous movement to cause the shoe on a last to be gripped at opposite sides of the last, mechanism for effecting shoe gripping movement of said members, and manually adjustable means determinately to vary the amount of gripping movement of said members effected through said mechanism. 105
26. In a machine for effecting the separation of a shoe and its last by relative movement of last holding means and shoe gripping means, opposed members connected for 110 relative movement to cause the shoe on a last to be gripped at opposite sides of the last, mechanism for effecting shoe gripping movement of said members, and means positioned and arranged for adjustment by the operator determinately to vary the amount of shoe gripping movement imparted to said members through said mechanism. 115
27. In a machine for effecting the separation of a shoe and its last by relative movement of last holding means and shoe gripping means, opposed members connected for 120 relative and simultaneous movement toward 125
- 130

- opposite sides of a shoe to grip the shoe between them, mechanism for effecting shoe gripping movement of said members, and a stop member positioned and arranged for 5 manual adjustment by the operator determinately to limit the amount of shoe gripping movement imparted to said opposed members through said mechanism.
28. In a machine for effecting the separation of a shoe and its last by relative movement of last holding means and shoe gripping means, clamping members arranged for relative movement toward the opposite sides of a shoe to clamp the shoe, a common 10 actuator for said members movable to actuate said members relatively to each other to clamp the shoe, mechanism for effecting movement of said actuator and adjustment means to vary the amount of movement of 15 said actuator.
29. In a machine for effecting the separation of a shoe and its last by relative movement of last holding means and shoe gripping means, opposed members connected for 20 relative movement to clamp a shoe and having a common actuator, mechanism for moving said actuator in a direction to move said members to clamp the shoe, and manually adjustable means arranged determinately to 25 vary the extent of said mechanically effected movement of the actuator determinately to 30 vary the amount of clamping movement of 35 said members.
30. In a machine for effecting the separation of a shoe and its last by relative movement of last holding means and shoe holding means, opposed members connected for 40 relative movement toward opposite sides of a shoe to clamp the shoe and having a common actuator, mechanism for moving said 45 actuator in a direction to effect clamping of the shoe, and manually adjustable means determinately to vary the amount of shoe clamping movement effected through said actuator.
31. In a machine for effecting the separation of a shoe and its last by relative movement of last holding means and shoe gripping means, opposed members relatively 50 movable to clamp a shoe, mechanism for causing relative shoe clamping movement of said opposed members including a common actuator for said members, and manually adjustable means determinately to limit the 55 shoe clamping movement of said actuator effected through said mechanism.
32. In a machine for effecting the separation of a shoe and its last by relative movement of last holding means and shoe gripping means, opposed members connected for 60 relative and simultaneous movement to effect the clamping of the counter portion of a shoe between them, mechanism for effecting counter clamping movement of said members, and 65 means positioned and arranged for manual adjustment by the operator determinately to vary the amount of counter clamping movement of said members effected through said mechanism.
33. In a machine for effecting the separation of a shoe and its last by relative movement of last holding means and shoe gripping means, opposed members connected for relative and simultaneous movement to clamp a shoe between them and having a common actuator, mechanism for moving said actuator in a direction to effect shoe clamping movement of said members, and a stop member positioned and arranged for 70 manual adjustment by the operator determinately to limit the amount of shoe clamping of said actuator effected through said mechanism.
34. In a machine for effecting the separation of a shoe and its last by relative movement of last holding means and shoe gripping means, opposed members relatively movable to clamp a shoe between them, power operated mechanism for causing relative shoe clamping movement of said members including a common actuator for said members, and manually adjustable means for determinately varying the amount of shoe clamping movement of said actuator effected by said power operated mechanism.
35. In a machine for pulling a last from its shoe by movement of last holding means relative to shoe gripping means, opposed members relatively and simultaneously movable toward opposite sides of a shoe to grip a shoe between them, power operated mechanism for causing relative shoe clamping movement of said members including a common actuator for said members, power operated mechanism for pulling the last from the gripped shoe, and means positioned and arranged for manual adjustment by the operator determinately to vary the amount of power operated shoe clamping movement of said actuator.
36. A machine of the class described having, in combination, last holding means, opposed members connected for relative and simultaneous movement to grip the counter portion of a shoe between them and having a common actuator, mechanism for effecting counter gripping movement of said actuator, manually adjustable means for determinately varying the amount of counter gripping movement of said actuator effected through said mechanism, and mechanism for effecting relative movement of said last holding means and said shoe gripping means to separate a shoe and its last.
37. A machine of the class described having, in combination, last holding means, opposed counter gripping members mounted for movement toward opposite sides of a shoe to grip the counter portion of the shoe between them, connections between said

members to cause them simultaneously to move toward the shoe including a common actuator, mechanism operative to effect shoe gripping movement of said actuator, means 5 positioned and arranged for adjustment by the operator determinately to limit the amount of gripping movement of said members, and mechanism for effecting relative movement of said last holding means and 10 said shoe gripping means to separate a gripped shoe and its last.

38. In a machine for effecting the separation of a shoe and its last by relative movement of last holding means and shoe 15 gripping means, opposed members connected for relative and simultaneous movement to cause the shoe on a last to be gripped between them, mechanism for effecting relative shoe gripping movement of said members, and a threaded stop coöperating with 20 said mechanism and positioned and arranged for adjustment by the operator determinately to limit the amount of shoe clamping movement imparted to said members through said mechanism.

39. A machine for effecting the separation of a shoe and its last by relative movement of last holding means and shoe gripping means having opposed shoe grippers 30 able to engage and hold the shoe between them for last and shoe separation and constructed and arranged to permit the shoe and last manually to be pulled from between said grippers by the operator during the period of separation and without moving the 35 grippers to release the shoe.

40. A machine for effecting the separation of a shoe and its last having, in combination, last holding means and shoe counter and 40 heel grippers relatively movable to separate a last and shoe, said grippers being effective to hold the shoe for the pulling of the last and being constructed and arranged to permit the shoe and last manually to be 45 withdrawn from said grippers by the operator during the pulling of the last from the shoe.

41. A machine for effecting the separation of a shoe and its last having, in combination, 50 last holding means, shoe grippers and power operated mechanism for relatively moving said last holding means and shoe grippers to separate a last and shoe, said grippers being effective to hold the shoe for last and shoe 55 separation and being constructed and arranged to permit the shoe and last manually to be pulled from said grippers during the period of separation and without moving the grippers to release the shoe.

60 42. A machine for effecting the separation of a shoe and its last by movement of last holding means relative to shoe gripping means comprising grippers yieldingly to clamp the counter portion of the shoe and 65 last between them and rigid shoe heel grip-

ping means unyieldingly opposing relative lengthwise rearward movement of the shoe, said contour and heel gripping means being constructed to permit manual withdrawal of the gripped shoe and last from said gripping means during the pulling of the last from the shoe. 70

43. A machine for effecting the separation of a shoe and its last having, in combination, last holding means mounted for swinging and bodily movement downwardly to pull a last from a gripped shoe, and shoe gripping means effective to hold the shoe for the removal of the last and comprising means yieldingly to grip the counter portion of the shoe and last and rigid heel abutment means unyieldingly to oppose relative lengthwise rearward and downward movement of the shoe, said shoe gripping means being constructed to permit forcible bodily 80 withdrawal of the shoe and last forwardly and downwardly during the pulling of the last from the shoe. 85

44. In a machine for effecting the complete separation of a shoe and its last the 90 combination with shoe gripping means, last holding means, and mechanism for effecting relative movement of said means to separate a shoe and its last, of mechanism operative prior to said relative separating movement to pull lengthwise rearwardly the 95 back-stay portion of the top of a shoe.

45. In a machine for effecting the separation of a shoe and its last the combination with shoe gripping means, last holding 100 means, and mechanism for effecting relative movement of said means to separate a shoe and its last, of a member arranged to be positioned inside the top of a shoe to engage the backstay portion of the shoe top and 105 means independent of the last and shoe-separating mechanism to pull said member lengthwise rearwardly of the shoe.

46. In a machine for effecting the separation of a shoe and its last the combination 110 with shoe gripping means, last holding means, and power operated mechanism for effecting relative movement of said means to separate a shoe and its last, of means operative independently of the mechanism for 115 effecting said relative separating movement to pull backwardly lengthwise of the shoe the backstay portion of the top of a shoe.

47. In a machine for effecting the separation of a shoe and its last the combination 120 with last holding means, shoe gripping means and power operated mechanism for effecting relative movement of said means to separate a shoe and its last, of means operative independently of the mechanism 125 for effecting said relative separating movement to pull backwardly lengthwise of the shoe the backstay portion of the top of a shoe in timed relation to and prior to said relative separating movement. 130

48. In a machine for effecting the complete separation of a shoe and its last the combination with last holding means, shoe holding means, and power operated mechanism for effecting relative movement of said holding means completely to separate a shoe and last, of a member constructed and positioned to engage the inside backstay portion of the top of a shoe, and mechanism arranged to move said member backwardly lengthwise of the shoe in timed relation to the separation of the shoe and last. 5
49. In a machine for effecting the separation of a shoe and its last by relative movement of last holding means and shoe gripping means, means arranged to be moved to grip the shoe, and means constructed and arranged to engage and pull backwardly lengthwise of the shoe the back stay portion 10 of the top of a shoe coincidently with the movement of said shoe gripping means to grip the shoe. 15
50. In a machine for effecting the separation of a shoe and its last by movement of last holding means relative to shoe gripping means to pull the last from a gripped shoe, shoe gripping means movable to grip a shoe on its last, and mechanism coöperating with said gripping means and operated 20 by movement of said means to pull lengthwise backwardly the backstay portion of the top of a shoe. 25
51. In a machine for effecting the separation of a shoe and its last by relative movement of last holding means and shoe gripping means, opposed members relatively movable to grip the shoe between them, mechanism for effecting gripping movement of said members, and means actuated 30 through said mechanism for pulling backwardly lengthwise of the last the back stay portion of the top of a shoe to provide clearance for the heel of the last. 35
52. In a machine for effecting the complete separation of a shoe and its last the combination with last holding means, shoe gripping means, and mechanism for effecting relative movement of said means completely to separate a shoe, and last, of a 40 horn member to engage the inside backstay portion of the top of a shoe, and mechanism to pull said horn lengthwise rearwardly of the shoe prior to the separation of the shoe and last. 45
53. In a machine for effecting the separation of a shoe and its last the combination with shoe gripping means, last holding means, and mechanism for effecting movement of the last holding means to pull the last from 50 the shoe, of a horn member constructed and arranged to engage the inside backstay portion of the top of a shoe and movable to stretch said portion lengthwise rearwardly of the shoe to facilitate the pulling of the 60 last heel from the shoe. 65
54. In a machine for effecting the separation of a shoe and its last the combination with shoe gripping means, last holding means, and mechanism for effecting movement of the last holding means to pull the last from its shoe, of a horn member constructed and positioned to engage the inside backstay portion of the top of a shoe, and mechanism for yieldingly pulling said horn member lengthwise rearwardly of the shoe 70 to provide clearance for the heel of the last. 75
55. In a machine for separating a shoe and its last the combination with last holding means, shoe gripping means, and mechanism for moving said holding means to pull the last from its shoe, of a substantially U-shaped member having one arm arranged to engage the inside of the rear extremity of the top of a shoe and having its other arm supported for movement with the first arm 80 lengthwise heelward of the shoe. 85
56. In a machine for effecting the separation of a shoe and its last the combination with last holding means, shoe gripping means and mechanism for relatively moving said means to separate a shoe and its last, of a substantially U-shaped member having one arm arranged to engage the inside of the rear extremity of the top of a shoe and having its other arm supported for swinging 90 movement with the first arm lengthwise rearwardly of the shoe and mechanism for effecting swinging movement of said arms. 95
57. In a machine for separating a shoe and its last by movement of last holding means relatively to shoe gripping means to withdraw the last, shoe grippers movable to engage a shoe, a horn arranged to engage the inside backstay portion of the top of a shoe and supported for movement lengthwise heelward of the shoe, mechanism for operating said grippers, and means operated through said mechanism for moving said horn lengthwise heelward coincidently with shoe clamping movement of the grippers. 100 105
58. In a machine for effecting the separation of a shoe and its last by relative movement of last holding means and shoe gripping means, opposed shoe gripping members constructed and arranged to be moved to and held in positions to present their opposed shoe engaging faces in predetermined angular relation converging rearwardly of the shoe. 110 115
59. In a machine for effecting the separation of a shoe and its last by relative movement of last holding means and shoe gripping means, opposed shoe gripping members and holders in which said members are mounted and which are constructed and arranged for independent angular adjustment to present the opposed shoe gripping faces of said members in determinate angular relation and determinately to vary said angular relation. 120 125

60. In a machine for effecting the separation of a shoe and its last by relative movement of last holding means and shoe gripping means, opposed shoe gripping members constructed and arranged for adjustment to present their opposed shoe engaging faces in determinate angular relation, converging rearwardly of the shoe and means yieldingly to hold said gripping members 5 in clamping engagement with opposite sides of a shoe.
61. In a machine for effecting the separation of a shoe and its last by relative movement of last holding means and shoe gripping means, opposed shoe gripping members, supported for straight line movement toward opposite sides of the shoe and having rearwardly converging shoe engaging faces, means for adjusting said members de- 10 terminately to vary the angle of convergence of their faces, and means yieldingly to move said members into clamping engagement with opposite sides of the shoe.
62. In a machine for pulling lasts from 15 shoes by movement of last holding means relatively to a gripped shoe, shoe gripping means comprising opposed counter grippers mounted for relative movement toward opposite sides of a shoe to grip its counter 20 portion between them, and constructed and arranged for swinging adjustment to present their opposed shoe gripping faces in determinate angular rearwardly converging relation and determinately to vary the angular 25 relation of said faces.
63. In a machine for effecting the separation of a shoe and its last by relative move- 30
- ment of last holding means and shoe gripping means, opposed shoe gripping members supported for movement toward and 40 from opposite sides of the shoe and having rearwardly converging shoe engaging faces, each of said members comprising a supported base having a curved seat and a gripper element mounted upon and deter- 45 minately adjustable about said curved seat.
64. In a machine for effecting the separation of a shoe and its last by relative movement of last holding means and shoe gripping means, opposed shoe gripping members having gripping faces extending in a straight line longitudinally of the shoe ar- 50 ranged for relative movement to grip oppo- site sides of the shoe to hold the shoe be- 55 tween them, said gripping members being constructed and arranged for adjustment to present their opposed gripping faces in angular relation converging rearwardly of the shoe.
65. In a machine for effecting the separation of a shoe and its last by relative movement of last holding means and shoe gripping means, opposed shoe gripping members constructed and arranged for relative bodily movement to grip opposite sides of 60 a shoe, and holders for said members mounted for adjustment to move said members from a position with their gripping faces in substantial parallelism into variable determinate angular relations to each other and 65 to hold them in such determinate relations.

In testimony whereof I have signed my name to this specification.

MICHAEL F. BROGAN.
